MAGNETIC MIXER

John Hays Hammond, Jr., Gloucester, Mass.

Application November 19, 1949, Serial No. 128,337

1 Claim. (Cl. 259—108)

1

This invention relates to mixing machines for soda fountains and more particularly to mixing machines in which the container for the material to be mixed is held in position by means of magnetic attraction.

More specifically the invention provides a mixing machine which is provided with an annular magnet affixed to the machine and an annular ring of ferrous material attached to the container, which is held in operative position by means of the magnetic attraction between the magnet and the ring.

The invention also provides means for normally holding the stirring shaft in a raised position and then lowering it into an operative position when the machine starts to function.

The invention further provides means for automatically starting the motor when the container is placed in the operative position.

The invention also provides means for guiding the container into the proper position when it is placed in the machine.

The invention also consists in certain new and original features of construction and combinations of parts hereinafter set forth and claimed.

The nature of the invention, as to its objects and advantages, the mode of its operation and the manner of its organization, may be better understood by referring to the following description, taken in connection with the accompanying drawings forming a part thereof, in which

Fig. 1 is a side elevation partly in section of a magnetic mixer constructed in accordance with the invention, showing the parts in the inoperative condition.

Fig. 2 is a bottom plan view of the mixer taken on line 2—2 of Fig. 1.

Fig. 3 is side elevation similar to Fig. 1 showing the mixer provided with a container and in operative position.

Fig. 4 is a top plan view of the container shown in Fig. 3.

Fig. 5 is a fragmentary side elevation, partly in section, of a modified form of magnetic mixer, and

Fig. 6 is a section taken on the line 6—6 of Fig. 5.

Like reference characters denote like parts in the several figures of the drawing.

In the following description parts will be identified by specific names for convenience, but they are intended to be generic in their application to similar parts.

Referring to the form of the invention shown in the accompanying drawings and more par-

2

ticularly to Figs. 1 and 2 a mixing machine 11 is provided with a base 12 and an upright pedestal 13. Attached to the upper end of the pedestal 13 is a motor 14. Secured to the lower face of the motor 14 is a circular plate 15, which is made of any suitable non-magnetic material, such as brass or aluminum. Located between the plate 15 and the motor 14 are spacers 16.

Surrounding the circular plate 15 and secured thereto is a cone shaped guide 17 which is provided with a large notch 18 on the part facing the pedestal 13. Located in the notch 18 and secured to the pedestal 13 is a cylindrically shaped vertical guide 19.

Mounted on the under surface of the circular plate 15 is an annular shaped permanent magnet 21 which is notched as shown at 22 and 23. The magnet 21 is so magnetized that north and south poles are produced at the points indicated by the letters N and S. If so desired the annular magnet 21 may be divided into a plurality of short sections each having its own north and south poles.

Pivottally mounted in the pedestal 13 is a contact arm 25, one end of which is provided with a curved finger 26 which extends through holes 27 and 28 in the plate 15 and magnet 21 respectively. Normally the arm 25 is held in the position shown in Fig. 1 by means of a light tension spring 29. In this position the finger 26 projects slightly below the lower surface of the magnet 21. Mounted on but insulated from the arm 25 is a contact plate 31 which at suitable times engages two fixed contacts 32 and 33 which are connected in an electric circuit 34, which is connected to a suitable source of electricity 35 and to the winding of the motor 14, so that when the contact plate 31 engages the contacts 32 and 33, the motor 14 will operate.

If so desired the contact arm 25 could similarly control a circuit from the source 35 to an electromagnet which could replace the permanent magnet 21 thus providing a stronger electric field.

The electric motor 14 is provided with a shaft 37 which rotates in suitable bearings not shown and upon which is mounted the armature of the motor, which is preferably of the universal series wound type. End plates 42 are secured to the motor frame to hold the shaft 37 in position. The shaft 37 is provided with two concentric holes 43 and 44 of different diameters each extending approximately half way through the shaft.

Mounted in the shaft 37 and projecting into the hole 44 is a pin 45, which engages a spiral groove 46 provided in a rod 47 which is slidably

3

and rotatably mounted in the hole 44. Wound around the rod 47 is a compression spring 48 the upper end of which is attached to the rod 47 and the lower end to the shaft 37. A cap 49 is mounted on the top of the rod 47 and fits into the hole 43 in the shaft 37. The rod 47 projects downward through a hole 51 in the plate 15 and at its lower end is provided with vanes 52, mixing disc 53 and a propeller 54 which is pitched to exert a downward thrust on the rod 47 due to its rotation in the liquid in the container.

Referring to Figs. 3 and 4, a container 55 is shown which consists of an elongated cone shaped portion 56 to the top of which is attached a ring 57 of ferrous metal of the approximate size of the annular magnet 21.

Operation of Figs. 1-4

In the operation of the magnetic mixer depicted in Figs. 1-4, the ingredients which it is desired to mix are placed in the container 55, which is then placed in the position shown in Fig. 3. In placing the container in position it will be guided to the proper location by means of the conical guide 17 and the cylindrical guide 19. The container 55 will be held in this position against the force of gravity by means of the magnetic attraction between the annular magnet 21 and the ferrous-metal ring 57 which is in contact therewith.

When the container is placed in position the ring 57 will engage the finger 26 of the contact arm 25, which will be rotated in a clock-wise direction from the position shown in Fig. 1 to that shown in Fig. 3. This motion will cause the contact segment 31 to engage the fixed contacts 32 and 33, thus closing the circuit from the power supply 35 to the motor 14, which will start rotating in a counter-clockwise direction as indicated by the arrow in Fig. 2.

When the motor starts to rotate the parts will be in the position shown in Fig. 1. As the shaft 37 starts to rotate it will tend to carry the rod 47 with it in the same direction. Due, however, to the inertia of the rod 47 and the resistance caused by the vanes 52 and discs 53 in the material to be mixed, the rod 47 will tend to hold back and not to rotate as fast as the shaft 37.

This will result in a relative rotation between the shaft 37 and the rod 47 causing the pin 45 to move in the spiral groove 46 with the result that the rod 45 is moved down into the material to be mixed against the force of the spring 48, which at the same time is wound tighter about the rod 47 due to the relative rotation between the shaft 37 and the rod 47. When the pin 45 reaches the top end of the groove 46 the shaft 37 and the rod 47 will be locked together and both will rotate at the same speed.

After the mixing discs 53 have mixed the ingredients sufficiently the container 55 is removed from the machine 11 manually. When this occurs the pressure of the ring 57 on the finger 26 will be released allowing the contact arm 25 to rotate in a counter-clockwise direction under the action of the spring 29 from the position shown in Fig. 3 to that shown in Fig. 1. This in turn will break the circuit to the motor 14 causing it to stop.

As soon as the shaft 37 has come to a stop the spring 48 will tend to pull the rod 47 up and at the same time will tend to unwind. The combination of these two actions will cause the rod 47 to rotate in a counter-clockwise direction, as seen in Fig. 2, and to move up, thus causing the pin 45 to slide in the spiral groove 46 from the

position shown in Fig. 3 to that shown in Fig. 1.

The entire mechanism will now be in the position shown in Fig. 1 where it will remain until the container 55 is again placed in position, at which time the cycle of operations will be repeated.

Of course either the propeller 54 or the pin 45 and spiral groove 46 may be used independently if desired. In either case when the motor 14 stops the spring 48 will return the rod 47 to its initial position.

Referring to the modified form of the invention shown in Figs. 5 and 6, the mixer 61 is of the same general construction as that shown in Figs. 1 and 2 up to and including the electrical circuit 34. The motor 14 is provided with a shaft 62 having a longitudinal hole 63 therein. End plates 64 are secured to the motor frame to hold the shaft 62 in position. Slidably mounted in the hole 63 is a rod 65 made of non-magnetic material, which is provided with a longitudinal hole 66 the upper end of which is threaded as at 60. The rod 65 is also provided with two longitudinal slots 67. A pin 68 is provided which is secured in the shaft 62 and passes thru the slots 67, thus allowing the rod 65 to move up and down in the shaft 62, but preventing it from rotating with respect thereto. A cylindrical plug 69 is mounted in the hole 66 and is held against the pin 68 by means of a compression spring 71. A core 72 of magnetic material, such as soft iron, is provided with a threaded end 73 which is screwed into the threaded portion 60 of the rod 65 and holds the spring 71 in position.

Mounted on top of the motor 14 is a solenoid 75 having a laminated iron frame 76 and a winding 77, which surrounds the rods 65 and 72. The frame 76 is provided with clearance holes 78 thru which the rods 65 and 72 pass. A thin sheet metal cover 79 is provided which encases the motor 14 and the solenoid 75.

One side of the winding 77 of the solenoid 75 is connected by a conductor 81 to one side of a resistor 82 the other side of which is connected to a contact 83, which at suitable times engages the contact plate 31. A switch 84 is connected across the resistor 82, which may be used for short circuiting said resistor, when the solenoid 75 is operated on A. C. The other side of the winding 77 of the solenoid 75 is connected by a conductor 85 to the return conductor of the circuit 34.

Operation of Figs. 5 and 6

In the operation of the modified form of the invention depicted in Figs. 5 and 6, the container 55 is placed in position in a manner similar to that described in connection with Figs. 1-4. This will cause the arm 25 to be rotated in a clock-wise direction causing the contact segment 31 to engage the three contacts 32, 33 and 83.

This action will start the motor 14 rotating and at the same time will energize the solenoid 75 which will cause the iron core 72 to be pulled down into the solenoid 75. As the core 72 is attached to the rod 65 the latter will also be moved down against the action of the spring 71 which is compressed between the core 72 and the plug 69.

It is thus seen that as soon as the motor 14 starts the rod 65 will rotate due to the pin 68 in the slots 67 and at the same time it will be moved down into the ingredients in the container 55 which are thoroughly mixed due to the action of the mixing vanes 53.

This action will continue until the container 55 is removed thus allowing the arm 25 to return

to the position shown in Fig. 5 under the action of the spring 29. This will break the circuits to the motor 14 and the solenoid 75, thus causing the motor 14 to stop the rotation of the rod 65.

When the solenoid 75 is deenergized the core 72 will no longer be held in the down position, but will be moved upward together with the rod 65 under the action of the spring 71 until the parts have assumed their initial positions as shown in Fig. 5. The mixer will then remain in this condition until it is ready to be used again.

If the mixer is to be used with D. C. supply, it will be necessary to open the switch 84 thus throwing the resistance 82 in series with the solenoid winding 71.

Although only a few of the various forms in which this invention may be embodied have been shown herein, it is to be understood that the invention is not limited to any specific construction but may be embodied in various forms without departing from the spirit of the invention.

What is claimed is:

A mixing device comprising a container, a support to hold said container in position for stirring, a motor mounted on said support and having a hollow vertical shaft, a stirring rod mounted in said shaft to be driven thereby and sliding axially between retracted and stirring positions, spring means normally holding said rod in retracted position, a solenoid having a core attached to said rod and positioned to advance said rod downwardly when energized and circuit means including a container actuated switch to energize said solenoid.
